REVERSIBLE TOOTH FOR EARTH DIGGING EQUIPMENT

Gerald A. M. Petersen, P.O. Box 330A,
Santa Clara, Calif.

Filed Sept. 9, 1957, Ser. No. 682,720

The terminal portion of the term of the patent subsequent to Mar. 17, 1976, has been disclaimed

13 Claims. (Cl. 37—142)

This invention relates to a new and improved reversible tooth for earth-digging equipment, such as earth augers and the like. At the present time earth-digging equipment of various types employs a plurality of digging teeth which absorb much of the wear encountered by the tool and also are the portion of the equipment most likely to be broken. The present invention relates to a replaceable tooth for earth-digging equipment which is conveniently and rapidly replaceable and which further may be reversed so that when the tooth is worn on one side, it may be turned over and used on the other side.

This application comprises a continuation-in-part of my co-pending United States patent application Serial No. 620,291, filed November 5, 1956, now Patent No. 2,877,574, for Reversible Tooth for Earth-Digging Equipment.

Accordingly, one of the principal objects and advantages of the present invention is the provision of a tooth which may be attached to and removed from a shank plate or other portion of an earth-digging tool or other piece of similar equipment with a minimum of time and effort.

Another object and advantage of the invention is the provision of a reversible tooth which may be used first on one side and, when worn, may be turned over and used on the other side. One of the particular features of the invention is the facility with which the tooth may be reversed and, after having been reversed, securely locked in position with a minimum of labor and without the use of special tools or equipment.

Still another feature of the invention is the provision of cooperating means on the tooth and shank plate or other portion of the equipment to which the tooth is attached, which assist in securing the tooth in place.

A still further feature of the invention is the provision of cooperating means on the tooth and shank plate to which it is attached, which prevent the tooth from being displaced from its proper position when the tooth is subjected to severe stress, such as striking a hard object at one corner of the tooth.

One of the principal advantages of the instant invention is the fact that wear of the tooth occurs on its edge. In other forged replaceable teeth, the means of connection employs a stud and a socket. Wear occurs in the zone of connection between the stud and socket, which is particularly subject to abrasion and other frictional deterioration. Since the socket is conventionally a permanent part of the earth-digging equipment, deterioration of this part of the connection causes discard of the equipment, thereby defeating a primary reason for the use of replaceable teeth. The instant invention eliminates the socket principle and the tooth is wide enough to protect the underlying shank from wear; hence the shank is truly permanent and need not be replaced despite wearing out of many replaceable teeth.

Another object of the invention is to provide means whereby a tooth is formed having a slot extending forwardly of the proximal end thereof, which divides the tooth into two discrete portions at the proximal end. A

2

shank is provided having a step or recess shaped to receive at least a portion of the proximal end of the tooth and, further, having means extending through the slot and engaging the edges of the slot to hold the tooth in position in the shank. Further, the tooth and shank may be provided with cooperating means in the form of mating depressions and protuberances or other means hereinafter described in greater detail, which cooperate to prevent withdrawal of the tooth from the shank prior to the time when it is desired to reverse or replace the tooth.

An important feature of the present invention is the fact that the tooth is held in a shank and the shank is secured to the major piece of equipment, such as an auger, so that the tooth and even the shank may be replaced when worn or damaged, without the necessity of discarding the major piece of equipment.

Other objects of the present invention will become apparent upon reading the following specification and referring to the accompanying drawings, in which similar characters of reference represent corresponding parts in each of the several views.

In the drawings:

Fig. 1 is a perspective view of a portion of a piece of earth-digging equipment, such as an earth auger, with a plurality of teeth constructed in accordance with this invention attached thereto;

Fig. 2 is an enlarged sectional view taken substantially along the line 2—2 of Fig. 1;

Fig. 3 is an enlarged top plan view of a tooth and a portion of the adjacent shank;

Fig. 4 is a sectional view taken substantially along the line 4—4 of Fig. 3;

Fig. 5 is a view similar to Fig. 2 of a modified tooth;

Fig. 6 is a top plan of the structure of Fig. 5 with the bolt head removed;

Fig. 7 is a fragmentary view of a modified structure similar to that shown in Fig. 5;

Fig. 8 is a view similar to Fig. 2 of a modified tooth;

Fig. 9 is a side elevation of the tooth shown in Fig. 8;

Fig. 10 is a top plan thereof;

Fig. 11 is a view similar to Fig. 2 of a further modified tooth construction;

Fig. 12 is a top plan of the tooth shown in Fig. 11. The present invention relates to a reversible replaceable

tooth 11. As shown in Fig. 1 of the accompanying drawings, a plurality of such teeth may be attached to a piece of earth-digging equipment, such as an earth auger 12 of the type used to dig holes for utility poles. Reference is made to United States Patent No. 2,578,014 which illustrates an earth auger to which the present invention may be attached. As an integral part, or, as shown in the accompanying drawings, a separate part of such equipment, there is provided a shank plate 13 attached to the main portion of auger 12 by means of bolts 14. The shape of shank plate 13 varies considerably and the number of teeth 11 attached thereto is likewise the subject of variation. As illustrated in Fig. 1, one such shank plate 13 provides a means of attachment for three teeth 11, the attachment means for each tooth being substantially identical. Accordingly, the attachment of a single tooth to the shank plate will be described.

Shank plate 13 is formed with a plurality of outwardly projecting roots 16 corresponding in number to the teeth and disposed in a direction and at an angle to the axis of rotation of the tool which is determined by proper engineering design. The width of root 16 is substantially the same as the width of tooth 11 and the length of the root is sufficient to form a secure attachment. Each root 16 is cut away in a step having a back wall 17 substantially perpendicular to the direction of the tooth and a bottom wall 18 substantially parallel to the direction of

the tooth. The root is formed with an aperture 19 extending through bottom wall 18 adjacent the outer end of the root and centrally located relative to the sides thereof.

Projecting upward from bottom wall 18 are three protuberances 21, 21, 22. The two protuberances 21 are located inwardly of the central axis of aperture 19 and to either side thereof, and the third protuberance 22 is located midway of the sides of the root and forwardly of aperture 19. Protuberances 21, 22 are of a shape and have a function as hereinafter described.

Tooth 11 is formed of a hard piece of metal so as to absorb wear and withstand shock. Tooth 11 is of substantially the same width throughout, having parallel side edges 26 at least at its proximal end. The distal faces 27 of the tooth taper at an angle of approximately 6° and are truncated to form a forward end 28, thereby providing a first and a second cutting edge 29 on opposite faces of the tooth. One of the advantages of the present invention is the fact that the tooth may be used with one face upward and then reversed so that twice the wear may be obtained before the tooth need be replaced or resharpened. The proximal of the tooth has substantially parallel top and bottom faces 31 and 32 and rear end wall 33 perpendicular to faces 31 and 32 and side edges 26. Back end wall 33 of the tooth seats against back wall 17 of the step. A rectangular slot 34 extends forwardly from rear end wall 33 of the tooth and the length of slot 34 is such that, when a carriage bolt 36 is inserted in the slot 34 and through aperture 19, tooth 11 is properly located in position.

Both the top and bottom proximal faces 31 and 32 of the tooth are formed with three depressions 41, 41, 42 corresponding in position to the three protuberances 21, 21, 22 on shank plate 13. As shown in Fig. 4 and considering the depression 41 in the top proximal face 31, each of the rearward disposed depressions 41 extends across the width of the tooth from slot 34 to side edge 26. The forward wall 43 of depression 41 slopes downwardly-rearwardly at an angle of approximately 15° commencing along a line displaced rearwardly from the center line 44 of bolt 36 a short distance. The rear wall 46 of the depression slants downwardly-forwardly at an angle of 45° and intersects forward wall 43 to provide a maximum depth of the depression (as indicated by reference numeral 47) approximately one-quarter the thickness of the tooth.

Forward depression 42 has a width slightly greater than one-quarter the width of tooth 11 and has a depth approximately one-quarter the thickness of the tooth. Forward depression 42 is centrally disposed with respect to side edges 26 of the tooth and extends forwardly of forward wall 48 of slot 34 substantially horizontally a distance substantially equal to the width of depression 42. The forward wall 49 of depression 42 (as shown in Fig. 2 and considering the depression 42 in top face 31) slopes upwardly-forwardly at an angle of approximately 45°.

Protuberances 21, 21, 22 on shank plate 13 are, as has been stated, positioned and shaped to fit snugly within depressions 41, 41, 42. Accordingly the rearward protuberances 21 on either side are formed extending inwardly from side edges 26 a distance equal to the width between slot 34 and edge 26 of tooth 11. The rearward face 51 of protuberance 21 is disposed at an angle of 45° with respect to bottom wall 18, and front face 52 slants downwardly-forwardly at an angle of substantially 15°. Forward protuberance 22 has a width equal to the width of forward depression 42 on tooth 11 and a height equal to the depth thereof extending forwardly from aperture 19, and its corner edges are chamfered to assist in seating of the tooth.

Tooth 11 may be attached to shank plate 13 by a carriage bolt 36 having a square neck 56 under its head 57. The width of slot 34 is equal to the width of square neck 75

56 under head 57 of carriage bolt 36 and hence two sides of the square neck engage the side edges of slot 34 and a third side of the neck seats against front wall 48 of slot 34. When nut 58 is tightened on bolt 36, head 57 bears against top face 31 of tooth 11 and locks the tooth snugly to shank plate 13. The locking of the tooth to the shank plate is accomplished by the cooperation of the parts as heretofore described. Thus back face 33 of tooth 11 engages back wall 17 of shank plate 13 and bottom face 32 of the tooth engages bottom wall 18 of shank plate 13. In addition, protuberances 21, 21, 22 fit into depressions 41, 41, 42 and additionally neck 56 of bolt 36 engages the side and front walls of slot 34. In the event that tooth 11 strikes a hard object on one corner, protuberances 21, 21, 22 assist in preventing the tooth from being knocked out of alignment, inasmuch as they resist any twisting movement of the tooth.

It will be seen that, in order to remove a tooth 11, it is not necessary to remove nut 58 completely from bolt 36 or to remove bolt 36 from aperture 19. Nut 58 is loosened sufficiently so that protuberances 21, 21, 22 clear depressions 41, 41, 42, whereupon the tooth may be drawn forwardly by reason of the fact that there is provided a slot 34 instead of merely a bolt hole. This feature of the invention materially simplifies reversing the tooth or replacing the same.

After the tooth has been used until one cutting edge 29 is worn, the tooth is reversed, as has been indicated, and the other edge 29 used. When the tooth must be replaced or resharpened, the construction heretofore described expedites these operations.

The modified tooth forms shown in Figs. 5-14, inclusive, are similar in many respects to that form shown in Figs. 1-4, inclusive, and accordingly, for purpose of brevity, much of the foregoing description of the tooth and shank is omitted, corresponding parts of the tooth being given the same reference numerals in the accompanying drawings.

In the modification shown in Figs. 5 and 6, slot 34 is elongated as compared with Figs. 1-4 and the depressions 42 are eliminated. A protuberance 61 is formed extending up into slot 34 in a position ahead of neck 56 of bolt 36, and a second projection 62 extends up from bottom 18 of the step of shank 16a, in a position behind bolt head 56 and forwardly of rear wall 17. Projections 61 and 62 stabilize the tooth relative to the shank plate by preventing relative movement in any direction transverse to the axis of the bolt 36. It will be understood that the width of projection 61 is substantially equal to the width of the slot 34, but, as illustrated in Fig. 5, clearance, as indicated by reference numeral 63, exists between the front wall 64 of projection 61 and the forward wall of the slot. It will further be observed that forwardly of slot 34, both the top and bottom surfaces of the tooth are depressed, as indicated by reference numeral 65. The purpose of the depression 65 is to insure that, when nut 58 is drawn tight, the pressure is applied to the faces to either side of slot 34 to seat projections 21 in grooves 41. It will further be seen that the outer end of the shank is turned up, as indicated by reference numeral 68, so that its top surface engages the tapered surface of the distal of the tooth. This construction likewise assists in preventing the tooth from disengaging from the shank. To afford additional support, shank roots 16a are made wider than the tooth, rather than being of the same width.

Fig. 5 illustrates one of the features and advantages of the invention. Reference line 66 shows a representative line of digging when the tooth is new, whereas line of digging 67 shows how, even with considerable wear of the distal of the tooth, useful life thereof is maintained before the tooth need be replaced.

The modification of Fig. 7 is in many respects similar to that of Figs. 5 and 6 except for the fact that only one projection 61 extends up from the shank 16b so that the

space behind neck 56 of bolt 36 is clear, in the same manner as is shown in Fig. 2.

Figs. 8-10, inclusive, are similar to the modification shown in Figs. 5 and 6, except that the shape of tooth 81 differs. It will be understood that the shape of the tooth is subject to considerable variation. The tooth shown in Fig. 8 is designed for trenching machines. The distal corners 82 are beveled in top plan, and beveled facets 83 are formed at the corners, as best indicated in Fig. 10. It will be understood that other shapes of teeth may be employed in all of the modifications of the invention. This manner of fastening tooth 81 to its shank is essentially the same as in Figs. 5 and 6.

Figs. 11 and 12 illustrate a further modification of the invention. The proximal top and bottom faces 87 of tooth 86 are roughened or knurled and similarly the bottom face 88 of the step of the shank is knurled or roughened. It will be understood, further, that only one of the two surfaces 87 or 88 need be roughened, particularly when the tooth is not subject to as severe stresses as the teeth of the previous modifications are capable of absorbing. When the nut 58 is drawn tight on carriage bolt 36, the roughened surfaces grip against each other and prevent dislodgment of the tooth. It will be understood that a slot 89 is formed extending forwardly from the proximal end of tooth 86 and that this slot cooperates with square neck 56 of carriage bolt 36 to hold the tooth against displacement. The roughened surfaces 87 and 88 function in much the same manner as the projections 21, 22 and depressions 41, 42.

What is claimed is:

1. A tooth for an earth-digging tool comprising a unitary, hard piece of material having a tapered distal portion and a proximal portion formed with substantially parallel proximal external faces, said proximal portion being formed with a substantially rectangular slot extending forwardly from the proximal end of said tooth for the reception of fastening means in a direction transverse to said proximal external faces to form a pair of rectangular prongs, each of said proximal external faces being formed with a plurality of V-shaped depressions extending transversely across the width of at least one external surface of said prong, a first of said depressions being located rearwardly of the inner terminus of said slot and to one side thereof, and a second of said depressions being located rearwardly of the inner terminus of said slot and to the side thereof opposite to said first depression.

2. A reversible tooth for an earth-digging tool comprising a unitary, hard piece of material having an outwardly tapered distal portion truncated to provide a first and a second cutting edge disposed on opposite faces of said tooth, and a proximal portion formed with substantially parallel proximal external faces, said proximal portion being formed with a rectangular slot extending inwardly from the proximal end of said tooth to form a pair of rectangular prongs, the edges of said slot being substantially parallel to the side edges of said tooth, each of the top and bottom faces being formed with a V-shaped depression extending transversely across the width of said prong, a first of said depressions being located rearwardly of the inner terminus of said slot and to one side thereof, and a second of said depressions being located rearwardly of the inner terminus of said slot and to the side thereof opposite to said first depression.

3. A reversible tooth for an earth-digging tool comprising a unitary, hard piece of material having an outwardly tapered distal portion truncated to provide a first and a second cutting edge disposed on opposite faces of said tooth, and a proximal portion formed with substantially parallel proximal external faces, said proximal portion being formed with a substantially rectangular, vertical slot extending inwardly from the proximal end of said tooth to form a pair of rectangular prongs, the edges of said slot being substantially parallel to the side edges of

said tooth, each of the top and bottom faces of said prongs being formed with a depression extending transversely across the width of said prong, a first of said depressions being located rearwardly of the inner terminus of said slot and to one side thereof, a second of said depressions being located rearwardly of the inner terminus of said slot and to the side thereof opposite to said first depression, each of said first and second depressions being shaped with a rearward wall disposed extending forwardly inwardly at an angle of approximately 45° and a forward wall intersecting said rearward wall extending rearwardly inwardly at an angle of approximately 15°.

4. In combination in an earth-digging tool, a shank formed with at least one step therein having a rear wall and a substantially transverse bottom wall, said shank being apertured in said bottom wall, a plurality of protuberances on said bottom wall, a tooth formed of a unitary piece of material, the proximal of said tooth fitting into said step and abutting said rear and bottom walls thereof, said tooth having a tapered distal portion and a proximal portion formed with substantially parallel proximal external faces, said proximal portion being formed with an aperture for the reception of fastening means in a direction transverse to said proximal external faces, at least one of said proximal external faces being formed with a plurality of depressions, a first of said depressions being located rearwardly of the inner terminus of said aperture and to one side thereof, and a second of said depressions being located rearwardly of the inner terminus of said aperture and to the side thereof opposite to said first depression, said protuberances fitting into said depressions, fastening means passing through the aperture in the bottom wall of said step and through the aperture in said tooth and cooperating with said protuberances and depressions to secure said tooth to said shank against forces tending to twist said tooth relative to said shank, and a projection on said shank extending up into the forward portion of said slot ahead of said fastening means.

5. In combination in an earth-digging tool, a shank formed with at least one step therein having a rear wall and a substantially transverse bottom wall, said shank being apertured in said bottom wall, a plurality of protuberances on said bottom wall, a tooth formed of a unitary piece of material, the proximal of said tooth fitting into said step and abutting said rear and bottom walls thereof, said tooth having an outwardly tapered distal portion and a proximal portion formed with substantially parallel proximal external faces, said proximal portion being formed with a slot extending inwardly from the proximal end of said tooth, the edges of said slot being substantially parallel to the side edges of said tooth to define a pair of prongs, each of the top and bottom faces of said prongs being formed with a depression extending transversely across the width of at least one external surface of said prong, a first of said depressions being located rearwardly of the inner terminus of said slot and to one side thereof, and a second of said depressions being located rearwardly of the inner terminus of said slot and to the side thereof opposite to said first depression, said protuberances fitting into said depressions, and fastening means passing through the aperture in the bottom wall of said step and through the slot in said tooth and cooperating with said protuberances and depressions to secure said tooth to said shank against forces tending to twist said tooth relative to said shank.

6. In combination in an earth-digging tool, a shank formed with at least one step therein having a rear wall and a substantially transverse bottom wall, said shank being apertured in said bottom wall, a plurality of protuberances on said bottom wall, a tooth formed of a unitary piece of material, the proximal of said tooth fitting into said step and abutting said rear and bottom walls thereof, said tooth having an outwardly tapered distal portion and a proximal portion formed with substantially parallel proximal external faces, said proximal portion being

formed with a vertical substantially rectangular slot extending inwardly from the proximal end of said tooth to form a pair of rectangular prongs, the edges of said slot being substantially parallel to the side edges of said tooth, each of the top and bottom faces of said prongs being formed with a depression extending transversely across the width of said prong, a first of said depressions being located rearwardly of the inner terminus of said slot and to one side thereof, and a second of said depressions being located rearwardly of the inner terminus of said slot and to the side thereof opposite to said first depression, each of said first and second depressions being shaped with a rearward wall disposed extending forwardly inwardly at an angle of approximately 45° and a forward wall intersecting said rearward wall extending rearwardly inwardly at an angle of approximately 15°, said protuberances fitting into said depressions, and fastening means passing through the aperture in the bottom wall of said step and through the slot in said tooth and cooperating with said protuberances and depressions to secure said tooth to said shank against forces tending to twist said tooth relative to said shank.

7. In combination in an earth-digging tool, a shank formed with at least one step therein having a rear wall and a substantially transverse bottom wall, said shank being apertured in said bottom wall, a plurality of protuberances on said bottom wall, a tooth formed of a unitary piece of material, the proximal of said tooth fitting into said step and abutting said rear and bottom walls thereof, said tooth having a distal portion tapering outwardly and a proximal portion formed with substantially parallel proximal faces, said proximal portion being formed with a slot extending inwardly from the proximal end of said tooth, the edges of said slot being substantially parallel to the side edges of said tooth, each of said proximal faces being formed with a plurality of depressions, a first of said depressions being located rearwardly of the inner terminus of said slot and to one side thereof, and a second of said depressions being located rearwardly of the inner terminus of said slot and to the side thereof opposite to said first depression, said protuberances fitting into said depressions, and a carriage bolt having a square neck passing through the aperture in the bottom wall of said step and through the slot in said tooth, said slot being dimensioned whereby two sides of said neck of said bolt abut the sides of said slot and a third side of said neck abuts the inner end of said slot, said bolt cooperating with said protuberances and depressions to secure said tooth to said shank against forces tending to twist said tooth relative to said shank.

8. In combination, in an earth-digging tool, a unitary shank shaped to receive the proximal end of a tooth, a tooth formed of a unitary piece of material and having its proximal end shaped to fit said shank, said tooth having top and bottom forwardly converging tapered distal faces, and a substantially rectangular proximal portion rearward of said distal faces having substantially parallel top and bottom external surfaces and a longitudinally forwardly extending, substantially rectangular slot extending forwardly from the proximal end of said tooth extending through from said top to said bottom surface and dividing said proximal end into two discrete prongs each substantially rectangular in shape, at least one surface of each said prong being formed with a shallow depression extending transversely across said prong, and means carried by said shank to restrain dislodgement of said tooth from said shank, said means engaging said depressions, said prongs being imperforate and no portion of said means extending inside said prongs.

9. The combination of claim 8 in which said means extends through said slot detachably holding said tooth and shank in engagement with each other and in which said means comprises cooperating means on said tooth and shank to restrain dislodgement of said tooth from said shank.

10. The combination of claim 8, in which said shank is formed with a step shaped to receive a part of the proximal of said tooth and the portion of said shank formed with said step is also formed with an aperture and said last-mentioned means comprises fastening means extending through said slot and aperture in said shank to draw said tooth toward said shank to engage said cooperating means when said fastening means is operative and to permit disengagement of said cooperating means when said fastening means is inoperative.

11. The combination of claim 10 which further comprises a second protuberance extending up into said slot behind said fastening means.

12. In combination, in an earth-digging tool, a unitary shank shaped to receive the proximal end of a tooth, a tooth formed of a unitary piece of material and having its proximal end shaped to fit said shank, said tooth having top and bottom forwardly converging tapered distal faces, and a substantially rectangular proximal portion rearward of said distal faces having substantially parallel top and bottom external surfaces and a longitudinally forwardly extending substantially rectangular slot extending from the proximal end of said tooth extending through from said top to said bottom surface and dividing said proximal end into two discrete prongs each substantially rectangular in shape, and means carried by said shank to restrain dislodgement of said tooth from said shank, said means engaging said prongs, said prongs being imperforate and no portion of said means extending inside said prongs, said means extending through said slot detachably holding said tooth and shank in engagement with each other and in which said means comprises cooperating means on said tooth and shank to restrain dislodgement of said tooth from said shank, said shank being formed with a step shaped to receive a part of the proximal end of said tooth and the portion of said shank formed with said step is also formed with an aperture and said last-mentioned means comprises fastening means extending through said slot and aperture in said shank to draw said tooth toward said shank to engage said cooperating means when said fastening means is operative and to permit disengagement of said cooperating means when said fastening means is inoperative, said slot extending substantially forward of said aperture, and a first protuberance on said shank extending up into said slot between said fastening means and the forward end of said slot.

13. The combination of claim 12, which further comprises side depressions on said tooth on either side of said slot and side protuberances on said shank positioned to fit into said side depressions.
